(57) **CLAIM**

I claim the ornamental design for a display screen or portion thereof with graphical user interface, as shown and described.

DESCRIPTION

FIG. 1 is a front view of a display screen or portion thereof with graphical user interface;

FIG. 2 is a front view of a second embodiment of the display screen or portion thereof with graphical user interface;

FIG. 3 is a front view of a third embodiment of the display screen or portion thereof with graphical user interface; and, FIG. 4 is a front view of a fourth embodiment of the display screen or portion thereof with graphical user interface.

The broken lines in FIGS. 1-4 depicting the display screen, text/words, numbers, symbols and other shapes in the graphical user interface form no part of the claimed design.

1 Claim, 4 Drawing Sheets
